Patented Apr. 20, 1976

239,660

PAINT ROLLER OR THE LIKE

James D. Tyson, Carthage, and R. G. Harris, Lexington,
N.C., assignors to Tyson Paint Roller Company,
Carthage, N.C.

Filed Sept. 6, 1974, Ser. No. 503,651

Term of patent 14 years

Int. Cl. D8—05

U.S. Cl. D64—18

FIG. 1

FIG.2

FIG. 5

FIG. 6

FIG. 4

FIG. 3

FIG. 1 is a top plan view of a paint roller or the like showing our new design;

FIG. 2 is a bottom plan view thereof;

FIG. 3 is a side elevational view thereof;

FIG. 4 is an elevational view of the opposite side thereof;

FIG. 5 is a view thereof taken from the handle end;

FIG. 6 is a view thereof taken from the roller end.

We claim:

The ornamental design for a paint roller or the like, as shown.
